ARTHUR McDougall DUCKHAM, OF LONDON, ENGLAND

METHOD OF AND APPARATUS FOR REPAIRING HEATED STRUCTURES SUCH AS
FURNACES, RETORTS, OR THE LIKE

Application filed May 15, 1929, Serial No. 363,396, and in Great Britain May 24, 1928.

The difficulty of repairing heated structures such as furnaces, retorts and the like by filling with jointing mixture cracks that may have developed in the structural material, is associated with the difficulty of locating the crack and causing penetration of the jointing mixture into the crack. The position of the crack is generally indicated by a leak of combustible gas which becomes visible by an appearance of flame or by abnormal incandescence of surrounding brickwork due to surface combustion.

One known method of dealing with the crack consists in forcing jointing mixture by air pressure from a container through a pipe directed on to the crack. The proportion of water that must be present in a mixture which will flow through a pipe is considerable, and before sufficient solid jointing material has been injected into the crack, cooling has occurred and the crack has become invisible, making continued injection difficult; such sudden cooling has, moreover, a deleterious effect upon the brickwork and, further, the effect of applying such a dilute mixture is that the mixture is unnecessarily spread over the surface and the crack is bridged rather than entered, so that although it is temporarily stopped and disappears it is soon again leaking.

This invention is based on the conclusion that the jointing mixture should be less fluid than has hitherto been usual and should be injected into the crack by a single application which should suffice to seal the crack by proper penetration of the mixture into it. To render this possible a sufficient quantity of the jointing mixture must be injected into the crack with accuracy, quickly and with great force.

This invention relates to a method of repairing heated structures of the kind in question by bringing a charge of jointing mixture substantially into register with the crack and then projecting the charge into the crack by means of a suddenly developed or released force. The charge should not exceed the quantity estimated as likely to be required to fill the crack, because in addition to being wasted the excess would adhere to the sur-

face of the structure forming protuberances to which there are well-known objections.

It will be seen that the invention necessitates an apparatus which can be raised or lowered or thrust horizontally or otherwise into the furnace or retort by means of a carrying and guiding rod or the like, until opposite the crack to be filled, as contrasted with bringing the jointing mixture to the crack by means of a pipe leading from an apparatus outside the furnace.

The jointing material is preferably enclosed in a container having a discharge orifice which in operation is brought into alignment with the crack to be sealed; a pressure is suddenly created or released behind the mixture so that this is suddenly projected into the crack with great force. The pressure may be created by any suitable means such as by an explosive or by the sudden release of suitable liquid or gaseous pressure. The discharge orifice may conveniently be a slot, considerably longer than it is wide, formed by tapering sides, so that by turning the container one way or the other, either horizontal or vertical cracks may be filled by bringing the major axis of the slot parallel to the direction of the crack. The container is preferably attached to a rod made up of separate lengths in well-known manner, so that it can be lengthened or shortened. If desired, more than one means of support or suspension may be used so as to minimize or obviate any tendency of the container to swing, and to cause it quickly to come to rest. In case the jointing mixture is to be projected by gaseous pressure created by the sudden expansion of a small charge of a compressed or liquefied gas placed in a container behind the charge of jointing mixture, this container may be explosively burst or a cap sealing an aperture in the container may open by thermal effect.

In the accompanying drawings,

Fig. 1 is an axial section,

Fig. 2 a plan, and

Fig. 3 an elevation of an apparatus, which may conveniently be called a cement gun, suitable for the invention.

Fig. 4 is a vertical section, and

Fig. 5 is a plan of a double barrel gun for comparatively heavy work.

Referring to Figs. 1-3, the cylindrical metal casing *a* has a tube *b* extending through it for reception of a cement container *c*. The latter is conveniently a tube fixed to a breech *d* and charged with jointing mixture. The breech contains an explosive cartridge *e* comprising a firing cap which is substantially in contact with the breech piece *f*.

The discharge end of the container *c* opens into a mouth piece *g* formed by two converging plates fixed to one end wall of the casing *a*. In the other end wall are screwed two pins *h*, one of which is surrounded by a sleeve *i* constituting a distance piece. On to this pin is threaded the breech piece *f* so that the latter can turn on the pin, a slot at the other end of the piece being adapted to engage the other pin *h* as indicated. When the breech piece is thus engaged it extends across the open end of the breech and can be held firmly thereto by screwing up the wing nuts *k*. The portion of the breech piece which closes the open end of the breech is of a good conductor of heat, for instance a copper inset *f'*.

The casing *a* is gripped by a strap *l* having a screw thread pin *m* for attachment of the first length of a rod which can be put together in lengths as required.

The operator is provided with a number of the firing units, each comprising a container *c* charged with jointing mixture, and a breech *d* containing explosive and a cap. The breech piece *f* having been released by unscrewing the wing nuts *k* and turned aside, the previously fired unit is withdrawn from tube *b*, a fresh unit is inserted and the breech piece *f* is closed and tightened. The rod attached to strap *l* is now used for bringing the casing *a* into position in the heated structure (for instance the casing is hoisted by means of the rod by an operator standing beneath a vertical retort), that is to say until the mouth-piece *g* is lengthwise substantially in alignment with the crack to be filled. When the casing has been in position for a few seconds the heat of the structure will penetrate through the breech plate to the firing cap and explode the cap, thus suddenly and rapidly discharging the cement from the container *c* into the crack.

The jointing mixture commonly used is made up with silicate of soda and, when charged into the container *c*, becomes covered at the end exposed to the air with a skin which suffices to retain the charge in the container until firing occurs.

Referring now to Figs. 4 and 5, the casing *a* carries trunnions *n* mounted to revolve in uprights *o* which spring from axles *p* having wheels *q*.

Fixed in the top and bottom of the casing

are two containers *c* each closed at the upper end by a breech *d* adapted to contain the cartridge *e* as explained in relation to Figs. 1-3. Fixed to the top of the casing are screw-threaded sockets *r* into which screw the breech pieces *f*, in each of which there is a copper inset *f'*, as described in relation to Figs. 1-3. The mouthpiece *g* is similar to that already described.

One of the trunnions *n* has an axial screw threaded bore into which can be screwed the end of the manipulating rod.

To use the gun, the breech pieces are removed, the cartridges are inserted in the breeches, and the breech pieces are replaced. The gun having been reversed on its axis, the known cement mixture is charged into the containers *c*. The cement (especially when containing sodium silicate) rapidly becomes covered on its exposed surface by a skim, sufficiently strong to permit of the gun being reversed on its axis without discharge of the cement. By means of the rod the gun is now wheeled on the internal surface of the retort or furnace to the required position in which the slot of the mouth *g* is more or less in register with the crack to be sealed, slight oscillations of the gun on its axis being possible, if necessary, by straining the rod. After a few seconds, the heat of the furnace penetrates the copper discs *f'* and the cartridges are fired to propel the cement through the mouthpiece into the slot.

In certain cases where the temperature of the walls of the heated structure under repair tends to fluctuate, difficulty may be encountered in regard to the exact time required to cause the firing of the explosive. In such cases the guns may be provided with a cap containing an electric resistance, the circuit leads of which extend through an insulating plug in the breech closure in place of the copper inset, and through the rod to a source of electric current under control of the operator. This mode of firing the gun makes the method independent of the temperature of the retort or furnace.

Having thus described the nature of the said invention and the best means I know for carrying the same into practical effect, I claim:

1. A method of repairing a crack in a heated structure of the kind referred to which consists in bringing a charge of repairing material substantially into register with a crack and applying a suddenly developed force to the charge to project it into the crack.

2. The method of repairing a crack in a heated structure of the kind referred to which consists in bringing a quantity of repairing material just sufficient to fill the crack to be repaired substantially into register with the crack, and then applying a suddenly developed force to the charge to project such

charge into the crack at a single application.

3. A method of repairing a crack in a heated structure of the kind referred to which consists in bringing a charge of confined repairing material substantially into register with a crack and then by a single suddenly developed force projecting the charge elongated transversely in one direction into said crack.

10 4. Apparatus for repairing a crack in a heated structure of the kind referred to comprising in combination a container for a charge of repairing material having an open mouth, means for holding an explosive charge in the container behind the charge of repairing material, means operable from the outside of the structure to be repaired for introducing the container into the structure and presenting its mouth substantially to a crack in the structure and means for exploding the explosive charge.

15 5. Apparatus for repairing a crack in a heated structure of the kind referred to comprising in combination a container for a charge of repairing material, said container having an open mouth, an elongated mouth-piece attached over said open mouth, a movable breech piece on the container rearwardly of said mouth, and means for holding an explosive charge in the breech piece in communication with the contents of the container.

20 6. Apparatus for repairing a crack in a heated structure of the kind referred to comprising in combination, a cylindrical casing having end pieces, a tube held between the end pieces to hold an open mouthed tubular container for repairing material, a breech piece carried by one of said end pieces and adapted to receive an explosive charge, means for holding the breech piece in position on said end piece, means for firing the explosive charge and a mouthpiece mounted on the other end piece of the said cylindrical casing.

25 7. Apparatus for repairing a crack in a heated structure of the kind referred to comprising an open ended container for a charge of repairing material, a movable breech piece on one end of the container and communicating with the interior of the latter means for holding an explosive charge in the breech piece, and means attached to the container for placing it in position in the structure to be repaired, said means being operable from the outside of such structure.

30 8. Apparatus for repairing a crack in a heated structure of the kind referred to comprising a tubular casing to contain a charge of repairing material, said casing having an open mouth at one end, a movable breech piece on the other end of said casing communicating with the interior thereof, means for holding an explosive charge in the breech piece, means attached to the container for placing it in position in a structure to be repaired and

35 operable from outside the structure and means operable by the heat of the structure for firing the explosive charge.

In testimony whereof I have signed my name to this specification.

70 ARTHUR McDougall DUCKHAM.
